UNITED STATES PATENT OFFICE.

JOHN F. REED, OF OTTUMWA, IOWA, ASSIGNOR TO J. U. YESSLER, OF LINN COUNTY, IOWA.

BUTTON-FEEDING MECHANISM FOR SHOE-BUTTON-ATTACHING MACHINES.

1,232,841.

Specification of Letters Patent. Patented July 10, 1917.

Application filed November 18, 1916. Serial No. 132,133.

To all whom it may concern:

Be it known that I, JOHN F. REED, a citizen of the United States, residing at Ottumwa, in the county of Wapello and State 5 of Iowa, have invented new and useful Improvements in Button-Feeding Mechanism for Shoe-Button-Attaching Machines, of which the following is a specification.

This invention relates to a button feeding 10 mechanism for shoe button attaching machines.

One object of the invention is to provide a button feed mechanism embodying a primary button guide or raceway which may 15 be automatically supplied from a hopper for general use and a secondary button guide or raceway which may be hand fed for occasional use, so that the machine may be normally employed for feeding and setting styles or kinds of buttons in most common use, and also employed when desired for feeding and setting fancy or special buttons or those not so commonly used.

A further object of the invention is to 25 provide a button feed finger which is adapted to be set for interchangeable use with the different button guides or raceways, for feeding buttons from either to a staple forming and button setting mechanism 30 common to both guides or raceways.

A further object of the invention is to 35 provide novel means for accurately guiding the buttons and feed finger, for positively insuring the engagement of the finger with the buttons, and for returning to the hopper any buttons which are not in position for a feed action, thereby obviating liability of choking or jamming of the buttons in the primary guide or raceway.

40 With these and other objects in view, the invention consists of the features of construction, combination and arrangement of parts hereinafter fully described and claimed, reference being had to the accompanying drawings in which:—

Figure 1 is a side elevation, partly in section, of the head of a shoe button attaching machine embodying my improved button feed mechanism.

50 Fig. 2 is a top plan view thereof.

Fig. 3 is a vertical longitudinal section.

Fig. 4 is a vertical transverse section

through the feed hopper, showing the button lifter in normal position.

Fig. 5 is a similar view showing the button lifter in raised or feeding position.

Fig. 6 is a detail view of the wiper or rejector.

Fig. 7 is a transverse section through the same and the upper portion of the primary 60 guide or raceway.

Fig. 8 is a perspective view of the hopper, 65 guide or raceways and guide elements co-operating therewith separated but arranged in proper relative positions.

Fig. 9 is a detail transverse section through the button guides or raceways, showing in full and dotted lines the interchangeable action of the feed finger.

The button feeding mechanism herein disclosed is adapted for general use in connection with any suitable type of staple forming and setting mechanism, but is preferably employed in conjunction with the type of staple forming and setting mechanism 70 disclosed in my copending application No. 133,925, filed Nov. 28, 1916. In the present application I have shown and described so much only of the staple forming and setting mechanism as will aid in securing a full 75 understanding of the construction and operation of the button feed mechanism, a full and specific showing and description of the staple forming and setting mechanism being regarded as unnecessary.

80 Referring to the drawings, 1 designates the head of the machine which is suitably secured to a base or table 2, mounted in the usual manner upon a frame column or pedestal 3 carried by a base 4, which base pivotally supports a main actuating or foot lever 5 normally held raised or retracted by a coiled spring 6.

85 Mounted upon the head 1 is a hopper 7 for containing the shoe buttons customarily used, which hopper communicates at its upper forward portion with a primary guide groove or raceway 8, down which the buttons supplied thereto slide by gravity to detent engaging position. This groove or 90 raceway 8 has a fixed receiving portion 9 disposed in the upper front portion of the hopper, and with which is adapted to aline an inclined button lifter bar 10 mounted for 100

vertical movement in the hopper, and adapted to collect and raise a number of buttons to feed by gravity to the portion 9 of the raceway and thence down the race-
5 way by gravity successively to detent engaging position. The raceway portions and lifter bar are provided with upper plane surfaces against which the flat base of the button rests and slides, and the grooves in
10 said raceway and lifter bar are designed to receive and accommodate the eyes of the buttons. For the purpose of rejecting or returning to the hopper any buttons upon the parts 9 and 10 which are improperly
15 positioned, I provide upon the hopper above the portion 9 a wiper or rejector 11 comprising a block of wedge-form having a recessed under surface 12 forming a cam face and adapted to receive the eyes of any but-
20 tons which are inverted, said cam surface and the inclined side of the wiper block acting to force the buttons laterally off the receiving section 9 from which they fall into the hopper to be later fed up. The
25 groove or raceway 9 is preferably arranged parallel with a secondary button guide groove or raceway 13 extending at its receiving end alongside the hopper, the said raceways converging at their lower ends into
30 a single guide slot 14, whereby buttons from either raceway may be directed into position to be engaged by a button feeder and fed forward to stapling position. The hopper, button and lifter and guideway 8 are
35 employed for feeding buttons commonly used, while the guide groove or raceway 13 may be employed for a hand feed in supplying special buttons of various kinds not so commonly used.

40 Arranged adjacent to the lower ends of the guideways are retaining springs or spring detents 15, one for each guideway, which detents are provided at their free ends with stop projections 16 extending over
45 the raceways and adapted to engage and hold the lowermost button of a column of buttons in position to be engaged and moved forward to staple forming position by the action of a button feed finger. Disposed
50 above the major portion of the guideways is a cover plate 17 having a forked lower end forming spaced guide fingers 18 and a slot or opening 19 in rear of and communicating with the space between the tips of
55 said fingers, said slot being disposed above the delivery groove 14. Disposed upon the slotted portion of the plate is a button finger guide or deflector 19 having side guide or deflector flanges 20 and 21 and having
60 the forward edge of its body portion cut out to form recesses 22 and 23 and an interposed V-shaped deflector 24, said recesses being adapted to overlie the rear portion of the slot 19 and the converging lower ends
65 of the respective grooves 8 and 13, to ex-

pose buttons in said grooves so as to be en-
gaged and moved forward by the action of the button feed finger 25.

The button feed finger 25 is provided with a lower finger portion proper 26 and an upper arm 27, the portion 26 being pro-
70 vided at its lower edge with a curved recess
28 to engage the head of a button disposed
in position to be fed, as shown in Fig. 3.
The finger is pivotally mounted to swing
laterally at a point between its portions 26
and 27, as indicated at 29, upon a rod or
axle member 30, so that the finger may be
disposed for co-operation with either one
of the grooves 8 or 13. The rod or axle 80
member 30 is pivotally mounted in a bearing
member 31 carried by a button feed
lever 32, in such a manner as to permit the
finger to have swinging movements for a
back and forth sliding action over the guide-
ways, for feeding a button out of engage-
90 ment with one of the stops 16, as indicated
in Fig. 3, forwardly to stapling position
shown in Fig. 1, the finger being allowed by
its pivotal connection to maintain engage-
ment with the button and move through a
substantially straight path while the lever
32 swings in an arcuate path. A coiled
spring 33 surrounds the rod 30 and is ter-
minally connected with the rod and bearing
95 member 31 to exert pressure on said rod so
as to constantly, but yieldingly, force the
finger downward toward the raceways. A
second spring 34 is connected at one end
100 with the rod 30 and at its opposite end with a pivoted finger shifter 35 having a finger
piece 36, said shifter being movable to en-
gage the finger proper or its arm 27 above
or below the pivotal connection 29, to hold
the finger 26 pressed laterally in one direc-
105 tion or the other beyond a straight vertical
position, to adapt the finger to engage a
button at the lower end of either groove 8
or 13, the spring 34, while maintaining the
finger normally in either operative position,
110 allowing it to have lateral movement for
travel between the raceway and delivery
groove, as will be readily understood. A
button disposed in either raceway may
therefore be engaged and fed forward
115 through the inclined lower end of the groove
and into the delivery groove 14. The finger
is guided in its motions between the grooves
8 and 14 by the flange 20 and adjacent side
120 of the deflector 24, in which operation the
notched end of the finger moves through
the recess 22, and the finger is guided be-
tween the grooves 13 and 14 by the flange
21 and adjacent side of the deflector 24, in
125 which operation the finger moves through
the recess 23. Through this capability of
adjustment and yielding vertical and lateral
movements of the finger, it will be evident
that it may be set for feeding buttons from
either feed groove or raceway at will, and
130

to follow the lines of the grooves for delivering a button from either raceway into the groove 14 for the staple forming and setting actions. When the finger is disposed 5 to hold the button in staple forming position, as shown in Fig. 1, it is arranged between the extremities 18 of the cover 17, and in such position is held from lateral movement, so that it will firmly hold the 10 button in position for the passage through its eye of the wire from which the staple is to be formed.

The button feed lever 32 is pivotally mounted upon the head frame, for backward 15 and forward swinging movements, as indicated at 37 and has a lower arm provided with a pin or stud 38 journaled therein and which is slotted or formed with an opening to slidably receive a motion transmitting rod 39, and said rod being pivotally connected at one end, as shown at 39', with one of the arms 40 of a bell crank lever 41, which arm 40 is coupled by a connecting rod 42 to the depressible actuating lever 5. The rod 39 20 extends at both ends beyond the pivot 38 and carries coiled springs 43 and 44, the spring 43 being arranged between the pin 38 and a nut or adjustable abutment 45 on the lower forward end of said rod 39, while 25 the spring 44 is disposed on the upper end of said rod 39 between the pin 38 and a suitable abutment member 46. The rod 39 is adapted when drawn downwardly by depression of the lever 5 to slide downwardly 30 and forwardly and thereby tension the spring 44, so as to transmit motion through said spring and the pin 38 to swing the upper arm of the button feed lever and the button feed finger carried thereby rear- 35 wardly to button engaging position as shown in Fig. 3. The springs 43 and 44 further serve to take up and compensate for any looseness due to wear, and thus insure a proper working action of the parts, and 40 also to permit the feed lever and finger to have a normal forward feed motion for feeding a button to stapling position, as well as an extended or abnormal motion for a purpose hereinafter described. The but- 45 ton lifter 10 is pivotally connected by a link 47 with another arm 48 of the bell crank lever, whereby when the finger is moved rear- 50 wardly the lifter will be elevated to carry a supply of buttons to the raceway portion 9, while when the finger is moved forwardly the lifter will be depressed for the next lifting action.

The link 47 is provided at its upper end with a slot 48' engaging a pin or screw 49 55 on the bar. A spring 50 is arranged to bear against the upper end of the link so as to normally maintain the pin, except when the link is lifted, at the upper end of the slot 48', said spring being carried by a depend- 60 ing portion of the lifter. The construction

described provides a yielding lost-motion connection between the link and lifter, whereby the lifter may be completely elevated into position to align with the raceway portion 9 before the button feed finger 70 completes its backward stroke, the link 47 continuing to move after the lifter is elevated to its fullest extent to the limit allowed by the slot 48'. Thus the lifter is adapted to remain stationary for a given 75 period during the retractive motion of the feed finger, so as to allow the buttons lifted thereby to travel fully into the raceway before the lifter is depressed and the feed finger moved forwardly on its feed motion. 80

The eye of the button is adapted when moved forwardly to staple forming position to engage a staple forming anvil 51 upon a vertically movable anvil and stop bar 52 normally held elevated by a spring 53 and 85 having a beveled abutment surface 54, in which position of the parts a section of wire to form the staple is passed through the eye of the button. This wire is engaged, on the ensuing retractive motion of the feed 90 finger, by staple forming and setting mechanism including dies, generally indicated at 55, which first form the staple against the anvil 51 and then clench the staple against the setting die 56, whereby the button is 95 moved forwardly to a setting position and fastened to the shoe or other fabric, one of the dies having a beveled abutment surface 57 to engage the abutment surface 54 of the member 52 whereby said member 52 and 100 anvil 51 will be moved out of the path of the dies on the setting motion. The dies 55 are operated in timed accord with the other parts by a gear connection with the bell crank lever, but I have not deemed it necessary to describe the staple forming and 105 setting mechanism in detail, as the same is not necessary to the disclosure and forms no part of the present invention. It may be stated, however, that the purpose in allowing the button feed lever 32 to have an extended forward motion beyond the position shown in Fig. 1, is to permit said button feed lever 32 to come forwardly to an extent to stop the motion of a wire feed device, to hold the same from a wire feed motion, as fully set forth in my aforesaid co-pending application. In this operation the yielding lost-motion connection between the bell crank lever and the button feed lever 110 115 permits of the operation of the die elements, in co-operation with a similar connection between the bell crank lever and die elements, to avoid injury to the working parts of the machine on such stop motion action. 120

From the foregoing description, taken in connection with the drawings, the construction and mode of operation of my improved button feeding mechanism will be readily understood, and it will be seen that the in- 125 130

vention provides a button feeding mechanism which is simple of construction, reliable and efficient in action, and adapted for use in feeding various kinds or styles of buttons in the manner specified. Also it will be seen that the invention provides for the interchangeable use of the button feed finger in connection with either button feed raceway, and that provision is made for taking up all lost-motion in the button feed mechanism due to wear and for permitting the certain working motions of parts without injury to others, whereby advantageous results are gained. The invention also provides for the more reliable and efficient feed of the button from the hopper to the button raceway, whereby proper feeding of the buttons is insured.

I claim:—

- 20 1. In a button attaching machine, a plurality of relatively stationary raceways having an outlet, and a button feeding device adjustable for coöperation with either of said raceways.
- 25 2. In a button attaching machine, a pair of button raceways, arranged to converge into a common outlet, a button feed lever, a button feed finger carried by the lever, and means for adjusting said finger for co-operation with either of said raceways to feed the buttons therefrom to said outlet.
- 30 3. In a button attaching machine, a pair of raceways having a common outlet, a button feed lever, a button feed finger pivotally mounted upon the lever for swinging movement in a direction longitudinally of the raceways, means pivotally mounting the finger upon said lever for yielding lateral motion, and means for adjusting the finger for coöperation with either of said raceways.
- 35 4. In a button attaching machine, a pair of raceways having a common outlet, a button feed lever, a yieldingly mounted button feed finger carried by said lever, said finger being pivotally movable both longitudinally and laterally, springs controlling the yielding action of said finger, and means for adjusting the finger for coöperation with either raceway.
- 40 5. In a button attaching machine, a pair of button raceways having a common outlet, a button feed lever, a finger pivotally mounted upon the lever for longitudinal and lateral swinging movements, springs controlling the action of said finger, means for adjusting the finger for coöperation with either raceway, and guiding means for guiding the finger between the outlet and raceways in the feed motions of said finger.
- 45 6. In a button attaching machine, a hopper, a raceway communicating therewith, a second raceway outside the hopper, said raceways being relatively stationary and having a common outlet in constant communication therewith, and feed mechanism

including a feed finger adjustable for co-operation with either raceway, and a feed device within the hopper for conveying buttons to the raceway communicating therewith.

70

7. In a button attaching machine, a hopper, a raceway communicating therewith, a button lifter arranged within the hopper, a pivoted member, an actuating lever therefor, a slot and pin connection between the lifter and the member, and a spring engaging said member for controlling said connection.

8. In a button attaching machine, a machine head having a hopper, a button raceway leading therefrom, a second button raceway arranged to be fed by hand independently of the hopper, button feed mechanism in the hopper, a feed device coöperating with the raceways, and adjustable for use with either raceway, and means for conjointly operating the button feeding means and feed finger.

9. In a button attaching machine, a hopper having an outlet, a grooved raceway having a fixed portion disposed within the hopper and registering with the outlet, a lifter movable within the hopper, an actuating device including a pivoted lever, a link pivoted at one end to said lever and having a slot and pin connection at its opposite end with the button elevating device, and a spring fixed to the lifter and bearing upon the latter-named end of the link to control said slot and pin connection.

100

10. In a button attaching machine, and in combination with a raceway, a button feed finger, a lever carrying said finger, an actuating lever, a rod pivotally connecting said levers and also slidably connected with the button feed lever, and springs disposed upon the rod on opposite sides of the pivotal connection between the same and the button feed lever and acting as motion transmitting devices.

110

11. In a button attaching machine, a plurality of button raceways having a common outlet, rigid therewith, a feed device for co-operation with said raceways, and means for adjusting said feed device for coöperation with one or the other of the raceways.

115

12. In a button attaching machine, a pair of raceways having a common outlet, a button feeding lever movable in a plane parallel therewith, a button feed finger pivoted to swing longitudinally and laterally upon said feed lever, springs controlling the pivotal movements of said feed finger, means for adjusting the finger for coöperation with either raceway and for movements between the said raceway and outlet, and means for transmitting motion to the button feed lever.

120

13. In a button attaching machine, a pair of relatively stationary button raceways having a common outlet, a button feed finger

130

movable longitudinally of the raceways and supported for pivotal lateral adjustment for coöperation with either raceway, and means for setting said finger for coöperation with either raceway.

14. In a button attaching machine, a pair of relatively stationary raceways leading to a common outlet, a button feed lever, a button feed finger pivotally supported upon the lever for longitudinal and lateral swinging movements, and means for adjusting said finger laterally for coöperation with either raceway.

15. In a button attaching machine, a hop-

per having an outlet, a grooved raceway 15 having a fixed portion disposed within the hopper adjacent to said outlet, a lifter vertically movable within the hopper, button feed mechanism including said lifter, and a cam device upon the front of the hopper, 20 comprising a block having an inclined outer face and a recessed under surface having an inclined portion opening through said inclined face, for deflecting from the stationary portion of the raceway improperly 25 positioned buttons.

In testimony whereof I affix my signature.

JOHN F. REED.
